UNITED STATES PATENT OFFICE.

MILTON H. SHOENBERG, OF SAN FRANCISCO, CALIFORNIA.

DESIGN FOR AN ELECTRIC CIGAR LIGHTER AND STANDARD.

Application filed May 22, 1922. Serial No. 2,351. Term of patent 14 years.

To all whom it may concern:

Be it known that I, MILTON H. SHOENBERG, a citizen of the United States, and a resident of the city and county of San Francisco, State of California, have invented a new, original, and ornamental Design for Electric Cigar Lighter and Standard, of which the following is a specification, reference being had to the accompanying drawing, forming part thereof.

Fig. 1 is a front view of an electric cigar lighter and standard showing my new design.

Fig. 2 is a side view of the same.

I claim:

The ornamental design for an electric cigar lighter and standard as shown.

MILTON H. SHOENBERG.
